UNITED STATES PATENT OFFICE

RANSOM W. DAVENPORT, OF DETROIT, MICHIGAN, ASSIGNOR TO CHICAGO PNEUMATIC TOOL COMPANY, OF NEW YORK, N. Y., A CORPORATION OF NEW JERSEY

REFRIGERATING AND ICE-MAKING APPARATUS

Application filed April 15, 1927. Serial No. 183,977.

This invention relates to apparatus for ice making and refrigeration generally with particular application to small refrigerating units intended for domestic use. More particularly the invention relates to closed cycle systems operating on the vapor-gas principle disclosed in my Patent No. 1,619,196 issued March 1, 1927, although by no means confined or restricted thereto in all of its aspects. 10 In many of my previous disclosures, such as that of my copending application, Serial No. 105,372 filed April 29th, 1926, it has been shown that distinct cooling and ice making elements are desirable in systems of the vapor-gas type and constructions have been disclosed in which the cooling element has large exposed area and the freezing element small area, which elements have been independently placed in separate chambers and exposed only to the contents of such chambers. 20

One object of the present invention is to improve upon previous constructions and principles. Another object is to simplify the construction and effect economies in manufacture. Still another object is to make refrigerating outfits of the described type more sanitary. Other objects will be apparent from the detailed description which follows: 25

The invention consists in providing a single refrigerating chamber in which the freezing and refrigerating elements or evaporators are mounted, these elements being preferably of the thin flat type such as disclosed in my aforesaid copending application, Serial No. 105,372, and in my copending application Serial No. 180,399 April 2, 1927. The freezing evaporator or freeze plate is disposed horizontally either at the bottom or at the top of the chamber, and containers for liquid to be frozen are arranged to be supported in thermal intimacy with the same. The cooling evaporator is disposed vertically within the chamber either as a separate partition or flat against the wall of the chamber. A removable drip plate is arranged to isolate a portion of the chamber adjacent the freeze plate from the rest of the chamber and collect the moisture which may drip upon or from the freeze plate and the liquid containers, depending upon the position of the same within the

chamber. The vertically disposed cooling evaporator may be of the concentrating type in the event that a lubricating refrigerant is used.

In order to illustrate the invention concrete 55 embodiments thereof are shown in the accompanying drawings in which;

Fig. 1 is a vertical sectional view through a self-contained refrigerating outfit for household use and illustrating one arrangement;

Fig. 2 is a sectional view similar to Fig. 1 showing a second arrangement;

Fig. 3 is a diagrammatic illustration of the closed cycle refrigerating apparatus used 65 in Fig. 2, and

Fig. 4 is a detail view on an enlarged scale of the container supporting arrangement of Fig. 2.

The embodiment of the invention shown in Fig. 1 comprises a refrigerator cabinet A having a chamber B formed with walls of heat insulating material and a machine compartment C beneath chamber B. Heat is extracted from chamber B by the vaporization 70 of a volatile liquid within two evaporators 4 and 5 connected in series and operating at the same total pressure. By preference the apparatus operates on the vapor-gas principle disclosed in my aforesaid Patent No. 1,619,196 and may comprise a pump or compressor 6 of any suitable or desired type driven by a prime mover, such as electric motor 7, and arranged to withdraw vaporized refrigerant from the top of evaporator 5 75 through a pipe 8 and discharge the same at higher temperature and pressure into a condenser 9 whence the working substance is fed back through a suitable feeding device or expansion valve 10 into evaporator 4 at a point remote from the connection 11 between the two evaporators. The evaporators may be formed of plates slightly spaced apart as disclosed in my aforesaid copending application Serial No. 105,372 so as to present a 85 maximum of extended surface while occupying a minimum of space.

Evaporator 4 is disposed horizontally at the bottom of chamber B and evaporator 5 is disposed vertically against a wall of chamber 95 100

bers B as shown. Since evaporator 4 receives the initial discharge of the products of compressor 9 it operates at a temperature below freezing and is accordingly designated 5 as a "freeze plate". Evaporator 5 is constructed so as to operate at progressively higher temperatures in accordance with the disclosure of my copending application Serial No. 77,156 filed December 22, 1925, and 10 may be arranged to operate wholly or partly at temperatures above freezing. Containers 12 for liquid to be frozen are arranged in thermal intimacy with freeze plate 4 and may rest directly upon it as shown. A removable drip plate 13 isolates the portion of chamber B adjacent freeze plate 4 and which contains ice trays 12 from the remainder of the chamber and protects the same from drip.

The arrangement shown in Fig. 2 differs 20 from that shown in Fig. 1 in that the freeze plate is placed at the top of the chamber and the refrigerant first expands into this freeze plate at the top of the circuit and works downwardly through the cooling evaporator 25 to the pump. In this figure the refrigerator cabinet A is similar in all respects to that shown in Fig. 1, being provided with a refrigerating chamber B' and machine compartment C'. The machine elements in compartment C' may conform to those shown in Fig. 30 1. The conduit from condenser 9' leads upwardly and discharges through feeding device 10' into the horizontally disposed freeze plate 14 which is secured flat against the top 35 of chamber B' and is connected to the cooling evaporator 15 through a trap connection 16. Evaporators 14 and 15 as shown are of the cast plate type disclosed and claimed in my aforesaid copending application, Serial 40 No. 180,399. Cooling evaporator 15 is here shown secured flat against the back wall of chamber B' and may be formed of a pipe in looped flat coils forming pockets to adapt the system for use with a lubricating refrigerant, 45 the lubricant component of the same being concentrated as it is fed downwardly through evaporator 15 to the inlet connection to compressor 6'. The lower face of the freeze plate 14 is provided with depending undercut 50 projections 17 forming guides slidably to receive containers 18 for liquid to be frozen, these containers having extended side members cooperating with the slide ways on projections 17. A drip plate 19 is disposed beneath the freeze plate 14 and containers 18 to prevent moisture dripping from the same 55 from reaching the food chamber. This drip plate also serves to isolate a portion of chamber B' in a manner similar to drip plate 14 60 of Fig. 1.

From the above it will be apparent that the present arrangement simplifies the structure of refrigerating outfits in that a single chamber formed with walls insulated against heat 65 is adapted both for freezing liquid and for

the cooling of perishable articles with a minimum loss of space; that the evaporator elements utilized within the chamber are readily accessible and can easily be kept in a clean and sanitary condition; that the thin flat freeze plate with a drip pan placed beneath or above the same adapts either the upper or lower part of the chamber to be used for freezing liquids; that the placing of the liquid containers either directly upon or suspended directly from the freeze plate insures effective absorption of heat both by radiation and convection; and that the invention is particularly adapted to systems operating on the vapor-gas principle due to the fact that in such systems heat is absorbed by the evaporator elements at progressively higher temperatures thereby permitting a part of the evaporator means to be used for freezing and a part for cooling.

While the invention has been herein disclosed in what is now considered to be preferred forms thereof, it is to be understood that the invention is not limited to the specific details thereof, but covers all changes, modifications and adaptations within the scope of the appended claims.

I claim as my invention:

1. A mechanically operated refrigerating outfit having a chamber from which heat is to be extracted, a thin flat horizontally disposed heat absorbing unit in said chamber, and a container for liquid in thermal proximity to said unit.

2. A mechanically operated refrigerating outfit having a chamber from which heat is to be extracted, a thin flat horizontally disposed heat absorbing unit at one extremity of said chamber, and a container for liquids in thermal proximity to said unit.

3. A mechanically operated refrigerator having a chamber with walls insulated against heat, a horizontally disposed freeze plate in said chamber adjacent one extremity thereof, and a removable partition isolating that portion of the chamber adjacent said plate from the remainder of the chamber.

4. A mechanically operated refrigerator having a chamber with walls insulated against heat, a horizontally disposed freeze plate in said chamber adjacent one extremity thereof, and a container for liquid to be frozen in contact with said plate.

5. A mechanically operated refrigerator having a chamber with walls insulated against heat, a horizontally disposed freeze plate adjacent the top of said chamber, means for supporting a container for liquid beneath said plate and in thermal proximity thereto, and means isolating that portion of said chamber adjacent said plate and for catching moisture dripping from said plate and container.

6. A mechanically operated refrigerator having a chamber with walls insulated against heat, a horizontally disposed freeze

- plate adjacent the top of said chamber, means for supporting a container for liquid beneath said plate and in thermal proximity thereto, and a drip plate disposed beneath said freeze plate and in spaced relation thereto.
- 5 7. A mechanically operated refrigerator having a chamber with walls insulated against heat, a horizontally disposed freeze plate adjacent the top of said chamber, and guide means on the lower face of said plate for supporting containers for liquid in close thermal intimacy with said plate.
- 10 8. A refrigerator cabinet having a chamber with walls insulated against heat, refrigerating apparatus for extracting heat from said chamber including a thin flat evaporator element disposed horizontally in said chamber, and means on said evaporator for suspending trays for liquid therebeneath.
- 15 9. A refrigerator cabinet having a chamber with walls insulated against heat, refrigerating apparatus for extracting heat from said chamber including a thin flat evaporator element disposed horizontally at the top of said chamber, means on said evaporator for suspending trays for liquid therebeneath, a drip plate removably supported beneath and in spaced relation to said element, and an additional evaporator element 25 in the main part of said chamber for extracting heat therefrom.
- 30 10. A refrigerator cabinet having a chamber with walls insulated against heat, refrigerating apparatus of the closed cycle type for extracting heat from said chamber comprising a horizontally disposed evaporator at one extremity of said chamber for taking in heat at a freezing temperature and a vertically disposed evaporator for taking in heat at a temperature above freezing, means connecting said evaporators in series and operating them at the same total pressure, and means for supporting containers for liquid to be frozen directly beneath and 35 in thermal intimacy with said freezing evaporator.
- 40 11. A refrigerator cabinet having a chamber with walls insulated against heat, refrigerating apparatus of the closed cycle type for extracting heat from said chamber comprising a horizontally disposed evaporator at the top of the chamber for taking in heat at a freezing temperature and a vertically disposed evaporator for taking in heat 45 at a temperature above freezing, means connecting said evaporators in series and operating them at the same total pressure, and means for supporting containers for liquid to be frozen directly beneath and in thermal intimacy with said freezing evaporator.
- 50 12. A refrigerator cabinet having a chamber with walls insulated against heat, refrigerating apparatus of the closed cycle type for extracting heat from said chamber comprising two thin flat evaporators connected 55 in series and operating at the same total pressure, one of said evaporators forming a freeze plate disposed flat against the top of said chamber and the other evaporator being disposed flat against a vertical wall of said chamber, and means on the lower face of said freeze plate for removably supporting containers for liquid to be frozen.
- 60 13. A refrigerator cabinet having a chamber with walls insulated against heat, refrigerating apparatus of the closed cycle type operating on the vapor-gas principle for extracting heat from said chamber comprising two thin flat evaporators connected in series and operating at the same total pressure, one of said evaporators forming a freeze plate disposed flat against the top of said chamber and the other evaporator being disposed flat against a vertical wall of said chamber, projections on the lower face of said freeze plate 65 providing slides, and containers for liquid having means cooperating with said slides thereby to support the same beneath and in thermal proximity to said freeze plate.
- 70 14. A refrigerator cabinet having a chamber with walls insulated against heat, refrigerating apparatus of the closed cycle type operating on the vapor-gas principle for extracting heat from said chamber comprising two thin flat evaporators connected in series and operating at the same total pressure, one of said evaporators forming a freeze plate disposed flat against the top of said chamber and the other evaporator being disposed flat against a vertical wall of said chamber, projections forming slides depending from the lower face of said freeze plate, containers for liquid arranged to be removably supported by said slides in thermal proximity to said freeze plate, and a drip plate beneath 75 said freeze plate and said containers.
- 80 15. A refrigerator cabinet having a chamber with the walls insulated against heat, refrigerating apparatus operating on the vapor-gas principle and utilizing a lubricating refrigerant for extracting heat from said chamber including two thin flat evaporators containing liquid refrigerant and connected in series, one of said evaporators forming a freeze plate disposed horizontally at the top of said chamber, the other evaporator being of the concentrator type for the lubricant component of the refrigerant and disposed vertically in said chamber, means for supporting containers for liquid to be frozen 85 directly beneath said freeze plate, and means isolating the portion of the chamber adjacent said freeze plate from the remainder of said chamber.
- 90 16. A refrigerator cabinet having a chamber with walls insulated against heat, refrigerating apparatus of the closed cycle type operating on the vapor-gas principle for extracting heat from said chamber comprising two thin flat evaporators connected in series and operating at the same total pressure, one of said evaporators forming a freeze plate disposed flat against the top of said chamber and the other evaporator being disposed flat against a vertical wall of said chamber, projections on the lower face of said freeze plate 95 providing slides, and containers for liquid having means cooperating with said slides thereby to support the same beneath and in thermal proximity to said freeze plate.
- 100 17. A refrigerator cabinet having a chamber with walls insulated against heat, refrigerating apparatus of the closed cycle type operating on the vapor-gas principle for extracting heat from said chamber comprising two thin flat evaporators connected in series and operating at the same total pressure, one of said evaporators forming a freeze plate disposed flat against the top of said chamber and the other evaporator being disposed flat against a vertical wall of said chamber, projections forming slides depending from the lower face of said freeze plate, containers for liquid arranged to be removably supported by said slides in thermal proximity to said freeze plate, and a drip plate beneath 105 said freeze plate and said containers.
- 110 18. A refrigerator cabinet having a chamber with walls insulated against heat, refrigerating apparatus operating on the vapor-gas principle and utilizing a lubricating refrigerant for extracting heat from said chamber including two thin flat evaporators containing liquid refrigerant and connected in series, one of said evaporators forming a freeze plate disposed horizontally at the top of said chamber, the other evaporator being of the concentrator type for the lubricant component of the refrigerant and disposed vertically in said chamber, means for supporting containers for liquid to be frozen 115 directly beneath said freeze plate, and means isolating the portion of the chamber adjacent said freeze plate from the remainder of said chamber.
- 120 19. A refrigerator cabinet having a chamber with walls insulated against heat, refrigerating apparatus of the closed cycle type operating on the vapor-gas principle for extracting heat from said chamber comprising two thin flat evaporators connected in series and operating at the same total pressure, one of said evaporators forming a freeze plate disposed flat against the top of said chamber and the other evaporator being disposed flat against a vertical wall of said chamber, projections on the lower face of said freeze plate 125 providing slides, and containers for liquid having means cooperating with said slides thereby to support the same beneath and in thermal proximity to said freeze plate.
- 130 20. A refrigerator cabinet having a chamber with walls insulated against heat, refrigerating apparatus of the closed cycle type operating on the vapor-gas principle for extracting heat from said chamber comprising two thin flat evaporators connected in series and operating at the same total pressure, one of said evaporators forming a freeze plate disposed flat against the top of said chamber and the other evaporator being disposed flat against a vertical wall of said chamber, projections forming slides depending from the lower face of said freeze plate, containers for liquid arranged to be removably supported by said slides in thermal proximity to said freeze plate, and a drip plate beneath 135 said freeze plate and said containers.

Signed by me at Detroit, in the county of Wayne and State of Michigan, this 8 day of April, 1927.

RANSOM W. DAVENPORT.

DISCLAIMER

1,769,117. — *Ransom W. Davenport*, Detroit, Mich. REFRIGERATING AND ICE-MAKING APPARATUS. Patent dated July 1, 1930. Disclaimer filed October 1, 1932, by the assignee, *Chicago Pneumatic Tool Company*, the patentee, said *Davenport*, assenting.

Hereby enters this disclaimer to that part of the claim in said specification which is in the following words, to wit:

“1. A mechanically operated refrigerating outfit having a chamber from which heat is to be extracted, a thin flat horizontally disposed heat absorbing unit in said chamber, and a container for liquid in thermal proximity to said unit.

“2. A mechanically operated refrigerating outfit having a chamber from which heat is to be extracted, a thin flat horizontally disposed heat absorbing unit at one extremity of said chamber, and a container for liquids in thermal proximity to said unit.”

“4. A mechanically operated refrigerator having a chamber with walls insulated against heat, a horizontally disposed freeze plate in said chamber adjacent one extremity thereof, and a container for liquid to be frozen in contact with said plate.”
